US0D1074727S

(12) **United States Design Patent** (10) Patent No.: **US D1,074,727 S**
 Adler (45) Date of Patent: ** May 13, 2025

(54) **DISPLAY SCREEN OR PORTION THEREOF WITH GRAPHICAL USER INTERFACE**

(71) Applicant: **OPEN WORKSPACE, LLC**, Highland Park, IL (US)

(72) Inventor: **David Adler**, Highland Park, IL (US)

(73) Assignee: **Open Workspace, LLC**, Highland Park, IL (US)

(**) Term: **15 Years**

(21) Appl. No.: **29/842,377**

(22) Filed: **Jun. 13, 2022**

Related U.S. Application Data

(63) Continuation-in-part of application No. 17/548,832, filed on Dec. 13, 2021.

CLAIM

The ornamental design for a display screen or portion thereof with graphical user interface, as shown and described.

DESCRIPTION

The FIGURE is a front view of a display screen or portion thereof with graphical user interface in accordance with my new design.

The outermost broken line rectangle shows the display screen or portion thereof and forms no part of the claimed design. All other broken lines show portions of the graphic user interface and form no part of the claimed design.

1 Claim, 1 Drawing Sheet
